(57) **CLAIM**

The ornamental design for a water closure, as shown and described.

DESCRIPTION

FIG. 1 is an isometric view of a water closure in accordance with my design;

FIG. 2 is a front view of the water closure of FIG. 1;
FIG. 3 is a left side view of the water closure of FIG. 1, the rear view and right side views being identical;
FIG. 4 is a top view of the water closure of FIG. 1; and,
FIG. 5 is a bottom view of the water closure of FIG. 1.
The dashed lines shown in the figures represent environmental subject matter and form no part of the claimed design.

1 Claim, 5 Drawing Sheets
